UNITED STATES PATENT OFFICE.

JOHN CHARLES BLEDSOE AND ADAM ALFRED BILYEU, OF TALALA, INDIAN TERRITORY.

VEHICLE-HUB.

SPECIFICATION forming part of Letters Patent No. 711,816, dated October 21, 1902.

Application filed June 24, 1902. Serial No. 113,023. (No model.)

To all whom it may concern:

Be it known that we, JOHN CHARLES BLEDSOE and ADAM ALFRED BILYEU, citizens of the United States, residing at Talala, in the 5 Cherokee Nation, Indian Territory, have invented a new and useful Vehicle-Hub, of which the following is a specification.

This invention relates to vehicle-hubs, and in particular to sectional hubs, the object of 10 the invention being to provide certain new and useful improvements whereby the hub-sections may be conveniently assembled in setting up the wheel and also adjusted to tighten the hub, the spokes, and the tire of 15 the wheel should any of these parts become loosened by wear. It is furthermore designed to provide for correcting the dish of the wheel without taking the latter apart and, in fact, without removing it from its axle.

20 With these and other objects in view the present invention consists in the combination and arrangement of parts, as will be herein-after more fully described, shown in the accompanying drawings, and particularly pointed 25 ed out in the appended claims, it being understood that changes in the form, proportion, size, and minor details may be made within the scope of the claims without departing from the spirit or sacrificing any of the advantages of the invention.

30 In the drawings, Figure 1 is a perspective view of a hub embodying the features of the present invention. Fig. 2 is a longitudinal sectional view thereof. Fig. 3 is a cross-sectional view on the line 3-3 of Fig. 2. Fig. 4 is a detail perspective view of the box or body of the hub. Fig. 5 is a detail perspective view of one of the spoke-sockets.

Like characters of reference designate corresponding parts in all of the figures of the drawings.

In carrying out the present invention there is provided a tapered cylindrical metallic box or tubular body portion 1, which has a smooth 45 tapered bore for the reception of an ordinary spindle 2 of the axle 3 and is externally screw-threaded at opposite ends, as shown at 4 and 5. At about the middle of the box or body, but slightly nearer the inner end thereof than 50 the outer end, is a circumferential series of longitudinally-disposed ribs 6, which project

at opposite sides of the member, but terminate short of the ends thereof. These ribs are formed integrally with the box and have their inner ends terminated in abrupt shoulders disposed at substantially right angles to the box and all in the same vertical plane, thereby forming a circumferential shoulder which lies at the inner end of the screw-threaded portion 4. The outer longitudinal faces 60 of the ribs are parallel with the adjacent portions of the box, and their outer ends are undercut, as at 7, so as to form tapered wedge-shaped overhanging shoulders, all of which combine with the box or body to form a tapered contracted circumferential seat. It will here be observed that the ribs 6 are spaced 65 at regular intervals, and therefore constitute an enlargement having a plurality of longitudinal grooves or seats.

70 For each of the grooves between the ribs 6 there is a spoke-socket 8, which is provided upon its under side with a reduced longitudinal rib or tongue 9 to fit in one of the grooves between the ribs 6, the lower faces of 75 the socket and the rib being longitudinally bowed or curved so as to rock upon the box or hub-body. The opposite longitudinal sides of the socket are tapered in opposite directions from the middle thereof toward its ends, 80 and these faces are also tapered transversely inward, whereby the socket is in the form of a wedge. Near the inner end of the socket is an outwardly-directed integral enlargement 10, which is provided in its outer end 85 with an oblong or polygonal recess or seat 11, and from this enlargement the outer faces of the socket are tapered in opposite directions to the ends thereof. As best indicated in Fig. 2, it will be seen that each spoke-socket is 90 longer than one of the ribs 6 and projects beyond the outer end of the latter.

95 For holding the spoke-sockets in place there is provided an inner terminal hub member 12 in the form of a band which is internally screw-threaded to fit the externally-screw-threaded portion 4 of the box. The inner end of the member forms a shoulder 13 to abut against the inner ends of the ribs 6 to limit the inward movement of the member, 100 and the latter is also provided at its inner end with a flared or substantially conical cir-

cumferential flange 14 to embrace the inner ends of the hub-sockets, thereby to form an abutment against which the inner ends of the spoke-sockets normally lie. The outer cylindrical end portion 15 of the band or hub member forms the inner hub-band, which is projected beyond the box and is provided upon its exterior with sets of diametrically opposite seats or notches 16 for engagement by a spanner-wrench to facilitate the application and removal of the hub member.

The outer end of the hub consists of a member made up of inner and outer band-sections 17 and 18, respectively, of which the inner member is internally screw-threaded throughout its outer half for engagement with the screw-threaded portion 5 of the box, while its outer portion is intermediately screw-threaded for engagement by the interiorly-screw-threaded portion of the section 18. The inner end portion 19 of the section 17 is smooth and tapered, so as to form a conical plug or wedge to pass beneath the outer ends of the spoke-sockets 8 and also beneath the beveled overhanging outer ends of the ribs 6. The outer end 20 of the section 17 is reduced and has a polygonal exterior, so as to form a wrench-seat, whereby the member 17 may be turned to feed the same inwardly and outwardly. The inner end portion 21 of the section 18 is flared outwardly, so as to embrace the outer projected end portions of the spoke-sockets, while the outer end portion 22 of the section is made cylindrical and provided with notches or seats 23 for engagement by a spanner-wrench to feed the section inwardly and outwardly upon the section 17 and independently thereof. Any ordinary form of hub-attaching nut 24 is applied to the projected screw-threaded end of the axle-spindle, so as to bear against the hub-body or box 1 to prevent displacement of the hub.

As best indicated in Figs. 2 and 3, it will be seen that the spokes 25 have their tenons 26 fitted into the seats of the spoke-sockets and are held therein by means of the rim and tire. (Not shown.)

From the foregoing description it will be seen that the present form of hub may be conveniently assembled and also taken apart whenever desired, and it will of course be understood that it is designed to have all of the parts made of metal, so as to provide a strong and durable hub.

To take up looseness and wear, the inner or wedge section 17 of the outer end of the hub is adjusted inwardly, so as to simultaneously rock or tilt all of the spoke-sockets, which has the effect of lengthening the spokes, as the tilting of the spoke-sockets spreads all of them radially outward, thereby drawing all of the parts of the hub into snug engagement and also forcing the rim outwardly into snug engagement with the tire.

When it is desired to give more dish to the wheel, the inner hub member 12 is backed off slightly from the spoke-sockets, the hub-

section 17 is also backed off slightly from the spoke-sockets, and then the outer hub-section 18 is adjusted inwardly, so as to bear upon the upper sides of the outer end portions of the spoke-sockets, and thereby shift the same endwise toward the abutment or hub member 12 and also to rock the same to throw the spokes outwardly, and thereby increase the dish of the wheel.

A very important feature of the present form of hub resides in the fact that it is not necessary to remove the wheel from the spindle in order that it may be adjusted to take up looseness or to correct the dish of the wheel. Moreover, the adjusting parts of the hub are located in position for convenient manipulation—that is to say, the parts 17 and 18 are located at the outer end of the hub, as these parts are more frequently adjusted than the inner end member 12, the latter being adjusted only when it is desired to correct the dish of the wheel, while the other parts are more frequently adjusted to take up wear and looseness.

Another important feature is that the part 12 forms means to prevent endwise slidable movements of the sockets when the latter are being tilted.

What we claim is—

1. A wheel-hub having a circumferential series of spoke-sockets, means for tilting the same, and means to prevent slidable movement of the sockets when being tilted.

2. A wheel-hub having a circumferential series of independent spoke-sockets, means for simultaneously tilting the same, and means to prevent slidable movement of the sockets when being tilted.

3. A wheel-hub, having a circumferential series of spoke-sockets which are tilttable longitudinally thereof, circumferential adjusting means carried by the hub in co-operative relation with the spoke-sockets for adjustably tilting the same, and means to prevent slidable movement of the sockets when being tilted.

4. A wheel-hub, having a circumferential series of tilttable spoke-sockets, means adjustably longitudinally of the hub toward and away from the sockets to adjustably tilt the latter, and means to prevent slidable movement of the sockets when being tilted.

5. A wheel-hub having a circumferential series of tilttable spoke-sockets, circumferential socket-adjusting means having a screw-threaded connection with the hub for movement toward and away from the sockets to tilt the same, and means to prevent slidable movement of the sockets when being tilted.

6. A wheel-hub having a circumferential series of tilttable spoke-sockets, a substantially conical wedge which is adjustably longitudinally of the hub to adjustably tilt the spoke-sockets, and means to prevent slidable movement of the sockets when being tilted.

7. A wheel-hub comprising a box, a circum-

ferential series of spoke-sockets which are tilt-
able longitudinally upon the box, a hollow
substantially conical wedge having a screw-
threaded engagement with the box and in co-
operative relation with the spoke-sockets to
adjustably tilt the same, and means to pre-
vent slidable movement of the sockets when
being tilted.

8. A wheel-hub having a circumferential
series of spoke-sockets which have rounded
edges to tilt or rock upon the hub, a circum-
ferential substantially conical adjusting-
wedge in frictional engagement with the
rounded edges of the spoke-sockets and ad-
justable toward and away from the same to
tilt them upon their rounded edges, and means
to prevent slidable movement of the sockets
when being tilted.

9. A wheel-hub, comprising a box, a circum-
ferential series of spoke-sockets having
rounded faces to tilt upon the box, a wedge-shaped
ring in frictional engagement with the outer
end portions of the rounded faces of the
spoke-sockets and adjustable toward
and away from the latter to tilt the same.

10. A wheel-hub, comprising a box, a circum-
ferential series of spoke-sockets which are tilt-
able upon the box, a wedge-shaped ring in
frictional engagement with the round-
ed faces of the spoke-sockets and adjustable
toward and away from the same, and an outer
substantially conical ring frictionally embrac-
ing the adjacent end portions of the
sockets and adjustable toward and away from
the latter upon the inner wedge-shaped ring.

11. A wheel-hub, comprising a box, a circum-
ferential series of spoke-sockets having
inner rounded longitudinal faces to tilt or
rock upon the box, an inner wedge-shaped
adjusting-ring screw-threaded upon the box
and frictionally inserted between the latter
and the adjacent ends of the spoke-sockets,
and an outer substantially conical ring fric-
tionally embracing the outer sides of the ad-
jacent end portions of the spoke-sockets and
screw-threaded upon the inner ring, the outer
end of the latter being projected beyond the
outer end of the inner ring to give access
thereto for adjustment, the two rings being
independently adjustable.

12. In a wheel-hub, the combination with
a box having its opposite ends externally
screw-threaded, of a circumferential series of
spoke-sockets disposed intermediately of the
box with their inner faces rounded to rock
upon the box, a substantially conical ring
frictionally embracing the inner ends of the
sockets and having internal screw-threads ad-
justably engaging the inner screw-threaded
end of the box, a substantially conical in-
ternally-screw-threaded ring adjustably fitted
to the outer screw-threaded end of the box
with its tapered portion frictionally inserted
between the adjacent ends of the spoke-sock-
ets and the box, and a substantially conical
ring screw-threaded upon the inner ring and

frictionally embracing the outer end portions
of the spoke-sockets.

13. In a wheel-hub, the combination with
a box, having an intermediate circumferen-
tial series of stationary longitudinal seats, of
tiltable spoke-sockets fitted in the seats, and
means carried by the box in co-operative rela-
tion with the sockets for tilting the same in
the seats.

14. In a wheel-hub, the combination with
a box having an intermediate circumferen-
tial series of spaced longitudinal ribs, a cir-
cumferential series of tiltable spoke-sockets
having longitudinal tongues fitted in the 80
spaces between the ribs to prevent sidewise
displacement of the sockets, and means for
tilting the spoke-sockets.

15. In a wheel-hub, the combination with
a box having an intermediate circumferential 85
series of spaced longitudinal ribs, a cir-
cumferential series of tiltable spoke-sockets hav-
ing longitudinal tongues fitting in the spaces
between the ribs, a substantially conical ad-
justing-ring embracing the inner ends of the 90
spoke-sockets and adjustable toward and
away from the same, a wedge-shaped or con-
ical ring adjustable longitudinally upon the
opposite end of the box and frictionally fit-
ting between the adjacent ends of the spoke-
sockets and the box, and a substantially coni-
cal ring adjustable longitudinally upon the
wedge-shaped ring and frictionally embrac-
ing the adjacent end portions of the spoke-
sockets.

16. In a wheel-hub, the combination with
an axle-box having its opposite ends exter-
nally screw-threaded and its intermediate
portion provided with a circumferential se-
ries of longitudinal spaced ribs, a circumfer-
ential series of spoke-sockets having their 105
inner faces rounded longitudinally and pro-
vided with longitudinal tongues fitting in the
spaces between the ribs, the outer ends of
the spoke-sockets being projected beyond the 110
ribs and the opposite ends of the sockets be-
ing beveled or tapered, a substantially conical
ring adjustably fitted to the screw-threaded
inner end of the box and frictionally embrac-
ing the adjacent ends of the spoke-sock-
ets, a tapered or wedge-shaped ring adjust-
ably fitted to the outer screw-threaded end
of the box with its inner end portion friction-
ally inserted between the box and the adja-
cent ends of the spoke-sockets, and a sub-
stantially conical ring frictionally embrac-
ing the outer end portions of the spoke-sockets
and adjustably screw-threaded upon the
wedge-shaped ring.

17. In a wheel-hub, the combination with a 125
box having opposite externally-screw-threaded
terminal portions and an intermediate cir-
cumferential series of longitudinal spaced
ribs which have their outer ends undercut, a
circumferential series of spoke-sockets hav-
ing inner rounded longitudinal faces to rock
or tilt upon the ribs, and also provided with

longitudinal tongues which fit between the ribs, each socket having an intermediate outwardly-directed enlargement provided with a recess or seat for the tenon of a spoke, and the ends of the socket being tapered outwardly in opposite directions, the outer ends of the sockets being projected beyond the ribs, a substantially conical ring adjustably fitted to the screw-threaded inner end of the box and frictionally embracing the inner ends of the spoke-sockets, the exterior of the ring having means for engagement by a wrench, a tapered ring adjustably fitted to the screw-threaded outer end of the box with its tapered portion frictionally inserted between the box and the outer ends of the spoke-sockets and also taking under the undercut ends of the ribs, the outer end of the ring having means for engagement by a wrench, and a substantially conical ring adjustably screw-threaded upon the tapered ring and frictionally embracing the outer end portions of the spoke-sockets, said ring being provided with means for engagement by a wrench.

18. A wheel-hub, comprising a box, a circumferential series of spoke-sockets which are shiftable longitudinally upon the box, an adjustable abutment carried by the box and at one end of the series of spoke-sockets, and adjusting means carried by the box for shift-

ing the sockets longitudinally of the box and into engagement with the abutment.

19. A wheel-hub having a circumferential series of spoke-sockets, which are independently tiltable and shiftable. 35

20. A wheel-hub having a circumferential series of tiltable and endwise-shiftable spoke-sockets, an adjustable abutment to limit the endwise movement of the sockets in one direction, and means coöperating with the other 40 end of the series of spoke-sockets to shift the same into engagement with the abutment and also to tilt the spoke-sockets.

21. A hub, comprising a box, a circumferential series of sockets having inner longitudinally-rounded edges lying against the box and adapted to rock or tilt thereon, means to rock or tilt the sockets upon their rounded edges, and means to prevent slidable movement of the sockets when being rocked or 45 tilted.

In testimony that we claim the foregoing as our own we have hereto affixed our signatures in the presence of two witnesses.
